BURGLAR ALARM SWITCHING SYSTEM

John T. Dooley, Buffalo, N. Y.

Application August 10, 1946, Serial No. 689,647

4 Claims. (Cl. 175—320)

1

This invention relates generally to certain new and useful improvements in burglar alarms, but more particularly to an electrically-governed alarm for safeguarding the public against burglary, hold-ups, fire, kidnapping, and the like.

It has for one of its objects to provide a device of this character which is self-contained, which is sensitive and positive and reliable in operation, and which is simple, inexpensive and sturdy as well as fool-proof, in construction.

Another object of the invention is to provide an alarm or body-protecting device which is so designed and constructed as to be rendered operative to sound an alarm whenever one attempts unauthorized intrusion on or into the premises in which the device has been installed to protect.

Other features of the invention reside in the construction and arrangement of parts herein-after described and particularly pointed out in the appended claims.

In the accompanying drawings:

Figure 1 is a front elevation of the burglar alarm device installed near the window of a room and being rendered operative by an intruder. Figure 2 is an enlarged sectional elevation thereof with the trapping cord in its retracted, inoperative position. Figure 3 is a cross section of the alarm device taken in the plane of line 3—3, Figure 4. Figure 4 is a longitudinal section of the alarm device taken on line 4—4, Figure 3. Figure 5 is a diagrammatic perspective view of the electric circuit and parts included therein.

Similar characters of reference indicate the corresponding parts throughout the several views.

The working parts of my alarm are housed in a casing or cabinet 10 providing a self-contained unit which can be placed where desired for protective use. In Figure 1, it is shown mounted on a chair with the actuating element or trapping cord 11 thereof extending adjacent a window 12 through which a burglar has partially entered and whose leg has contacted such cord and rendered the device operative to sound the alarm. The latter may be in the form of a bell 13 contained in the casing and deriving its power from a battery 14, also housed therein, as shown. If desired, however, other outside alarms may be included in the circuit or the device may be connected to the lighting circuit of one's home or building to cause all the lights in the house to go on when the alarm is rendered operative. The trapping cord 11 has an attaching eye 15 or the like at its free end for securing it in its extended position to some fixed point, such as 16.

Journalized in the casing 10 is a winding drum 17 about which the trapping cord 11 is wound,

2

its free end extending through the casing and having a pendant weight 18 thereon, as shown in Figure 2, for preventing back lash thereof during rewinding. The drum-shaft 19 has a pinion 20 thereon meshing with a driven gear 21 in driving engagement with a spring 22 fixed at its inner end to the gear-hub and at its outer end to a pin 23 fixed to a frame plate 24. This spring-driven mechanism constantly urges the cord to its retracted position, and, as will herein-after appear, any motion transmitted to the drum from a disturbance of the extended cord is utilized to insure closing certain contacts to render the alarm operative.

15 The numeral 25 indicates a manually-actuated slide or circuit control bar guided for horizontal movement within the casing 10 and at right angles to but in the axial plane of the drum-shaft 19. At its outer end this bar is provided with 20 a finger knob 26 and in the full line position thereof, shown in Figure 4, the alarm circuit is rendered inoperative while in the dotted line position of the bar the circuit is pre-set and in readiness to close when the trapping cord is in 25 any way tampered with. At its inner end this control bar has a contact 27 thereon terminating in an offset contact lug 28 in operative relation to a notched or bifurcated reset contact arm 29 loosely mounted on the drum-shaft. This arm 30 is yieldingly urged by a flat spring 30 or the like into lateral frictional engagement with the opposing cam face 31 of a collar 32 fixed on the drum-shaft 19, so that during turning of the latter the reset arm is free to oscillate laterally 35 and have as well a slight vertical rocking movement relative to the lug 28 to make an "on and off" sliding contact therewith. In the projected or inoperative setting position of the slide bar, its offset lug extends into and latches the contact 40 arm in a central or neutral position, so that when such bar is retracted to an operative setting position such lug is free from contact with the arm until such time as the cord 11 is disturbed, when the alarm is rendered operative.

45 Disposed alongside the bar contact 27 for circuit-closing engagement therewith in the retracted, operative setting position of the control bar 25 is a yielding contact 33 connected by a wire 34 to the coil of a magnet 35, the other side 50 of the coil being connected by a wire 36 to one of the contacts 37 of a distributing switch. The other contact 38 of this switch is connected by a wire 39 to the bell 13, the other terminal of the latter as well as the reset contact arm 29 being 55 connected to the grounded side of the battery 14. The other side of the battery is connected to a fulcrumming-like yieldable switch blade 40 fixed at

its looped end to the casing 10 and whose free end extends between the switch contacts 37, 38 and is normally urged upwardly by its own tension in closed relation to the bell-connected contact 38, but is forced downwardly in closed relation to the companion contact 37 by the lower end of an armature 41, pivoted intermediate its ends in operative relation to the magnet 35. The upper end of this armature is disposed in the path of a lug 42 on the control bar 25, so that in the inoperative setting positions of the latter such armature assumes the displaced position shown in Figure 5 and by full lines in Figure 4, wherein the switch blade 40 is closed across the contact 37 leading to the magnet coil. In the retracted operative setting position of the control bar its armature-engaging lug recedes therefrom and the contacts 27 and 33 are closed, with the armature remaining in its initial position due to its frictional edgewise engagement with the offset portion 43 of the yieldable switch blade 40. It is this circuit-prepared condition which the device assumes when it is set for use and to promptly sound the alarm when the cord 11 is disturbed. Should the cord be disturbed, for example, as shown in Figure 1, the drum 17 is partially turned and in so doing causes the reset contact arm 29 to make contact with the contact-lug 27 and momentarily close the circuit through the magnet 35. The energizing of the magnet attracts its armature and in so doing the latter is released from the switch blade 40 and the latter is automatically urged in switch-closing relation to the contact 38 to render the alarm 12 operative. When the control bar 25 is pushed inwardly the alarm circuit is opened and the parts assume the position shown in Figure 5.

If desired, a jack plug fitting 44 may be applied to the casing 10, and included in the control circuit of the device for shunting the current to an outside source to sound another alarm or to cause the house lighting circuit to be simultaneously closed when the alarm circuit is rendered operative and result in complete illumination of the house.

I claim as my invention:

1. An alarm-actuating switch mechanism, comprising an electric circuit including a magnet having an armature, a switch in said circuit including a yieldable blade movable to one or the other of two positions to establish the circuit of the magnet in one of such positions, said armature being disposed in frictional contact with said blade for normally releasably retaining said switch in one of its two positions, an auxiliary switch in said circuit including on and off presetting contacts and a third contact movable into circuit-closing relation with one of said on and off contacts, a manual control member on which one of said auxiliary switch contacts is mounted for opening and closing the same and disposed in operative relation to said third contact to render the same operative or inoperative, said control member having means thereon engageable with the armature for shifting the latter to its retracted normal position after it has been actuated to an operative switch-releasing position, a cord-winding drum including means for normally urging it to turn in a wind-up direction, and an operative connection between said drum and the third movable contact of said auxiliary switch for actuating such contact to an alarm circuit establishing position whenever the drum is caused to be turned.

2. An alarm-actuating switch mechanism, comprising an electric circuit including a normally-open switch including a yieldable blade, an auxiliary circuit including a second switch and magnet having an armature in endwise frictional engagement at one end with said yieldable blade for normally holding the first-named switch open and the armature releasably retracted and causing the closing of such switch and the release 10 of the armature when said magnet is energized, a pre-setting, manually-shiftable control member in governing relation to said second switch for causing its closing in one position thereof and its opening in its other position, an "on and 15 off," displaceable contact arm in operative relation to one of the elements of said second switch and included in the auxiliary circuit thereof for governing the energization of said magnet, and a rotatable connection to said contact arm for 20 causing its displacement to a position to close the auxiliary circuit and energize said magnet.
3. An alarm-actuating switch mechanism, comprising an electric circuit including a normally-open switch, an auxiliary circuit including a second switch and magnet having an armature in governing relation to first-named switch for normally holding it open and causing its closing when said magnet is energized, the free end of said armature being in camming relation to such 25 first switch to retain it open and the armature retracted, a presetting, manually-shiftable control member in governing relation to said second switch for causing its closing in one position thereof and its opening in its other position, and 30 an "on and off," displaceable contact arm in operative relation to one of the elements of said second switch and included in the auxiliary circuit thereof for governing the energization of said magnet.
4. An alarm-actuating switch mechanism, comprising an electric circuit including a normally-open switch, an auxiliary circuit including a second switch and magnet having an armature in governing relation to first-named switch for normally holding it open and causing its closing when said magnet is energized, the free end of said armature being in camming relation to such first switch to retain it open and the armature retracted, a presetting, manually-shiftable control 45 member in governing relation to said second switch for causing its closing in one position thereof and its opening in its other position, said control member having a part thereon releasably engageable with said armature for shifting it to a retracted position when such member is shifted to a switch-opening position, and an "on and off" contact arm in operative relation to one of the switch elements of said second switch and included in the auxiliary circuit thereof for governing 50 the energization of said magnet.
